[**] Term: 14 Years

[57] CLAIM

[21] Appl. No.: 930,584

The ornamental design for a water rescue wheel, sub-
stantially as shown.

[22] Filed: Aug. 2, 1978

DESCRIPTION

[51] Int. Cl. ..... D21—99

FIG. 1 is an oblique, top perspective view of a water
rescue wheel showing my new design;

[52] U.S. Cl. D21/99

FIG. 2 is a side elevational view thereof; and

[58] Field of Search 9/14; D21/237; D22/99

FIG. 3 is a bottom plan view thereof.

[56] References Cited

The rope shown in FIG. 3 is of indeterminate length
and FIGS. 1 and 2 eliminate for ease of illustration
detail of the rope shown in FIG. 3.
